STRIP FORMING APPARATUS

James S. Reid, Shaker Heights, Ohio, assignor,
by mesne assignments, to The Standard Products Company, Cleveland, Ohio, a corporation of Ohio

Application February 28, 1936, Serial No. 66,182

5 Claims. (Cl. 29—33)

This invention relates to strip-forming apparatus and more particularly, to apparatus for forming continuous lengths of a tacking strip consisting of a sheet metal channel member filled 5 with a plastic composition material, such as a rubber compound.

The general object of the present invention is the provision of improved apparatus for forming such a tacking strip, said apparatus including 10 means for bending continuous lengths of a flat metal strip member into channel shape and means for filling continuous lengths of such metal channel member with a plastic composition material.

More specific objects of the present invention, 15 and some of the features thereof, will appear from the following description of two embodiments thereof, reference being had to the accompanying drawings in which

Fig. 1 is an elevation, partly in section, showing one form of apparatus for forming the present tacking strip; Figs. 2 to 2c inclusive are perspective views showing the channel member of the tacking strip in various stages of its formation; Fig. 3 is a perspective view of the present 25 tacking strip; Figs. 4 to 7 inclusive are cross-sectional views of the apparatus of Fig. 1, the views being taken respectively on the lines 4—4 to 7—7 inclusive; Fig. 8 is a plan view showing another form of apparatus for forming the present tacking strip; and Figs. 9 and 10 are sectional views 30 of the apparatus of Fig. 8, taken respectively on the lines 9—9 and 10—10, Fig. 8.

The strip-forming apparatus shown in Fig. 1 and in Figs. 4 to 7 inclusive provides, upon a 35 suitable supporting frame work 14, a pair of rollers 15 for supporting a roll of sheet metal 16, said metal having a flat, ribbon-like cross-section, as indicated at A, Fig. 2. The metal strip of this roll passes over a guide roll 17, then through suitable 40 bending or forming means indicated generally at 18, which gives such metal strip a generally channel shape in cross-section, as indicated at D, Fig. 2c, and then through an extruding means indicated generally at 19, which fills such metal channel member with a plastic composition material, 45 such as a rubber compound, the finished tacking strip, as it emerges from the extruding means of the apparatus, being indicated at 20.

The bending or forming means 18 may consist 50 of suitable dies but is here shown as consisting of a series of pairs of cooperating rolls, each pair of rolls having bending or forming passes by means of which the metal strip shown in Fig. 2 is progressively given the cross-sectional forms or shapes indicated in Figs. 2a to 2c inclusive. In

other words, the pass between the first pair of rolls 18a bends or forms the metal strip as shown in B, Fig. 2b; the pass between the second pair of rolls 18b bends or forms the metal strip as shown at C, Fig. 2c; and the pass between the third pair of rolls 18c bends or forms the metal strip as shown at D, Fig. 2d, this being its finished form.

From said bending or forming means 18, the metal strip, which now has a generally channel shape in cross-section, enters the extruding 10 means of the present apparatus. The extruding means here shown includes a generally horizontally disposed tubular casing 21 within which is axially mounted a stationary mandrel 22, through the longitudinal passage-way 23 of which 15 the metal channel member passes, said passage-way having a cross-sectional shape and size to snugly receive said channel member so that said member is fully supported and properly guided in its travel through said passageway. Rotatable about this mandrel 22, within the casing 21, is a suitable feed screw 24, the rotation of which is here effected by a gear 26 rigidly secured there-to and meshing with a pinion 27 driven by a suitable electric motor 28. Adjacent its entrance 25 end, the casing 21 is provided with a suitable top opening 25, through which the plastic composition material is fed to the feed screw 24.

Bolted or otherwise suitably secured, in pressure-tight relationship, to the discharge end of 30 the casing 21, is an extruding head 29, into the chamber 29a of which the feed screw 24 discharges under pressure the plastic composition material which it receives through the casing opening 25. Arranged within the discharge end 35 of the feed screw 24, at the discharge end of the mandrel 22, is a suitable die 30, the opening 30a of which conforms to the cross-sectional shape of the metal channel member, as shown in Fig. 5, so that the plastic composition material discharged by the feed screw 24 into the extruding head chamber 29a cannot back up into those portions of said channel member which have not yet entered said chamber from the mandrel 22.

As best shown in Fig. 6, the chamber 29a of the 45 extruding head is formed by a generally U-shaped partition 31, which provides an effective support for the base and side wall portions of the metal channel member as it passes through said chamber, the top of said channel member being 50 open and thus in communication with such chamber for the forceful filling of such channel member with the plastic composition material discharged into such chamber by the feed screw 24. In the die plate 21a of the extruding head 55

29 is a centrally disposed opening 33 through which emerges the finished tacking strip, consisting of the metal channel member and its filling of plastic composition material, said die plate opening being of such size, as indicated in Fig. 7, as to correspond to the finished tacking strip in cross-section, and thus insuring the filling of the metal channel member of the strip to the top of its upper, inwardly extending flanges.

10 The rolls of the bending or forming means of the present apparatus may be driven by any suitable mechanism and the finished cross-sectional form or shape of the metal channel member (D, Fig. 2c) is such that said member may be propelled from the bending or forming means through the extruding means of the present apparatus. In other words, the cross-sectional form or shape of the metal channel member gives it sufficient rigidity that it may be driven through 15 the extruding means, and filled with the plastic composition material, without driving aid from another source. However, if assistance is needed in effecting the passage of said channel member through the extruding means, or if the metal 20 channel member is given a cross-sectional form or shape which does not lend itself to propulsion through the extruding means from the bending or forming means, a pair of pull rolls 34 may be provided for pulling the metal channel member 25 through both parts of the present apparatus. In such a case, the bending or forming means may consist of stationary bending or forming members instead of rotatable ones, all as will be readily understood.

30 In the form of apparatus shown in Figs. 8 to 10 inclusive, the bending or forming means, indicated at 35, and the extruding means, indicated at 36, are arranged at right angles to each other. The feed screw 37 of the extruding means 40 of this apparatus feeds the plastic composition material under pressure into the chamber 38 of an extruding head 38a, through which chamber the metal channel member is passed for the purpose of being filled with the plastic composition material. A suitable die 39, similar to that 45 shown at 30, Fig. 5, performs the corresponding function of preventing the plastic composition material from backing up along the metal channel member as it enters the extruding head chamber 38. Wall portions 40 and 41 of the extruding head 38a provide a proper guide and support for the metal base and side walls of the channel member while it is being filled, from above, with the plastic composition material, and a suitable opening 43, similar to that indicated at 33, Fig. 7, performs the corresponding function of insuring the filling of the channel member to the top of its upper, inwardly extending flanges.

45 The tacking strip thus formed by the present apparatus is particularly adapted for use in the automotive industry as an anchoring means for upholstery tacks, the metal channel member of the strip being capable of being readily secured, by spot-welding or the like, to metal surfaces 50 which are to be covered with upholstery or the like, and the plastic composition material of the strip being capable of readily receiving and permanently retaining the upholstery-securing tacks.

55 Further uses of the tacking strip, and further features of the apparatus by means of which it is formed, will occur to those skilled in the art to which the present invention relates.

What I claim is:

75 1. Apparatus for continuously forming a tack-

ing strip consisting of a metal channel strip containing plastic composition material, said apparatus comprising means for bending a flat metal strip into channel form, a tubular casing having an inlet opening for plastic composition material, a stationary guide tube extending longitudinally through said casing, a feed screw arranged within said casing for rotation about said guide tube, a chambered head secured to said tubular casing adjacent the discharge ends of 10 said feed screw and said guide tube, means for rotating said feed screw to discharge under pressure plastic composition material into the chamber of said head, said head having a discharge opening in alignment with the passageway through said guide tube, means for continuously passing a flat metal strip through said bending means to give such strip a channel form and for continuously passing the channel strip thus formed through said guide tube, through the 20 chamber of said head, wherein such strip is filled with plastic composition material, and through the outlet opening of said chamber, the passageway through said guide tube being of such size and shape as to support and guide said channel 25 strip during its passage therethrough, and a die at the discharge end of said guide tube having an opening in alignment with the passageway through said guide tube, said die opening having a size and a channel shape corresponding to 30 those of said channel strip.

2. Apparatus for continuously forming a tacking strip consisting of a metal channel strip containing plastic composition material, said apparatus comprising means for bending a flat metal strip into channel form, extruding means including a chamber and a feed screw for supplying plastic composition material thereto under pressure, and means for continuously passing a flat metal strip through said bending means to give 35 such strip a channel form and for continuously passing the channel strip thus formed through the chamber of said extruding means to fill said strip with plastic composition material, the path 40 of said strip through said bending means and 45 said chamber extending at right angles to the axis of said feed screw.

3. Apparatus for continuously filling an elongated channel shaped strip with plastic composition under pressure, said apparatus comprising 50 a part having a chamber, means for supplying plastic composition to said chamber under pressure, there being strip inlet and outlet openings in the walls of said chamber, said inlet and outlet openings closely corresponding to the cross 55 section of said unfilled and filled strip respectively, means between said openings providing a continuous support for the outer faces of the side and bottom walls of said channel strip, said last named means providing for access of plastic 60 composition from said chamber to the interior of said strip, and means for passing said strip through said openings and said chamber.

4. Apparatus for continuously filling an elongated channel shaped strip with plastic composition under pressure, said apparatus comprising a part having a chamber, means for supplying plastic composition to said chamber under pressure, there being strip inlet and outlet openings in the walls of said chamber, said inlet and outlet 65 openings closely corresponding to the cross section of said unfilled and filled strip respectively, and means for passing said strip through said openings and said chamber.

5. Apparatus for filling with plastic composi-

75

tion under pressure continuous lengths of a channel shaped strip having bottom and side walls and partial top wall flanges extending inwardly from said side walls, said apparatus comprising a part having a chamber, means for supplying plastic composition to said chamber under pressure, there being strip inlet and outlet openings in the walls of said chamber, said inlet and outlet openings closely corresponding to the cross section of said unfilled and filled strip respectively, means

between said openings providing a continuous support for the outer faces of the side and bottom walls and top wall flanges of said channel strip, said last named means providing for access of plastic composition from said chamber to the interior of said strip through the open portion of said top wall, and means for passing said strip through said openings and said chamber. 5

JAMES S. REID. 10
